WILLIAM F. DRAPER AND CLARE H. DRAPER, OF HOPEDALE, MASSACHUSETTS, ASSIGNORS TO DRAPER COMPANY, OF HOPEDALE, MASSACHUSETTS, A CORPORATION OF MAINE.

AUTOMATIC FILLING-REPLENISHING LOOM.

SPECIFICATION forming part of Letters Patent No. 725,229, dated April 14, 1903.

Application filed November 4, 1902. Serial No. 130,061. (No model.)

To all whom it may concern:

Be it known that we, WILLIAM F. DRAPER and CLARE H. DRAPER, citizens of the United States, and residents of Hopedale, county of 5 Worcester, State of Massachusetts, have invented an Improvement in Automatic Filling-Replenishing Looms, of which the following description, in connection with the accompanying drawings, is a specification, like characters on the drawings representing like parts.

This invention relates to looms the operation whereof is controlled by or through a feeler in accordance with the condition of the filling in the shuttle, a change in the operation 15 of the loom, such as a replenishment of filling or stoppage of the loom, being effected automatically upon substantial exhaustion of the filling in the running or working shuttle.

Looms of this type are well known to those 20 skilled in the art and are frequently designated as "feeler-looms," owing to the important function performed by the feeler. In such looms the feeler intermittently engages and is moved or vibrated by the filling 25 in the shuttle as the lay beats up, the filling-induced movement of the feeler gradually decreasing in amplitude as the filling weaves off until only so much remains in the shuttle as will cross the lay a few times. When such

30 substantial filling exhaustion is reached, a stoppage of the loom or a replenishment of filling is effected by suitable means, the feeler at such time having no filling-induced movement at all or so slight a movement as will

35 serve to effect the desired change in the operation of the loom. The feeler usually enters the shuttle through a hole in its side wall and contacts with the filling as the lay beats up, and manifestly the less the thickness of

40 filling interposed between the bobbin or filling-carrier and the contact end of the feeler the shorter will be the filling-induced movement of the latter, so that by adjusting the feeler and coöperating parts the waste or

45 quantity of filling remaining in the shuttle when the operation of the loom is changed will be very small. Such adjustment is in actual practice modified or affected by variability in the movement of the lay, due

principally to changes in the speed of the 50 loom and the looseness of connections, so that at one speed the lay when on front center may overrun or not quite reach the point reached by it when the loom is running at a different speed, and if the feeling mechanism 55 is adjusted for a given speed changes in the latter tend to throw the adjustment out very materially. Thus the feeler may effect a change in the operation of the loom too soon, with consequent waste of filling, or it may be 60 so delayed that the whole object of the device is defeated. We have herein devised novel means for overcoming or preventing such faulty operation of the feeler and in such a manner that great accuracy is attained in 65 the control of the loom by or through the feeler.

It is well known that the front wall of the shuttle-box is frequently adjusted in order that the shuttle shall box properly, according 70 to the size of the shuttle, the action of the picking mechanism, and other circumstances, and obviously a change in the front box-wall will effect a corresponding change in the position of the shuttle when boxed. Inasmuch 75 as the feeler must maintain a fixed relation with the longitudinal axis of the shuttle in order to properly feel the filling therein, means have been provided for effecting such positioning by or through the shuttle itself and 80 also by means independent of the shuttle. Our present invention is of the latter type, and we have provided means to properly position the feeler by or through the front wall of the shuttle-box on the forward beat of the 85 lay, so that when the weaver finds it necessary to adjust such front wall, thereby changing the position of the longitudinal axis of the shuttle when boxed, there will be a corresponding correction made automatically 90 when the feeler is positioned for its feeling action.

The various novel features of our present invention will be fully described in the subjoined specification and particularly pointed 95 out in the following claims.

Figure 1 is a top or plan view of a portion of the left-hand side of a loom with the lay

back and with one embodiment of our present invention applied thereto. Fig. 2 is a left-hand side elevation of the parts shown in Fig. 1, a part of the filling-feeder stand of 5 a filling-replenishing mechanism being shown. Fig. 3 is a rear elevation of the feeler, feeler-support, and stand, mounted opposite the left-hand shuttle-box of the lay. Fig. 4 is a partial sectional view on the irregular 10 line 4-4, Fig. 1, looking toward the right, but with the lay on its front center, it being supposed that the filling in the shuttle has been substantially exhausted. Fig. 5 is a top plan 15 view of the feeler-support detached. Fig. 6 is a similar view of the stand on which said feeler-support is fulcrumed; and Fig. 7 is a side elevation, enlarged, of the latch and its actuator on the line 7-7, Fig. 1, looking toward the right.

20 The breast-beam A⁴⁰, lay A³, having a shuttle-box B^X thereon, the front wall b^X of the shuttle-box, adjustably secured upon the lay by bolts 22 and having an aperture 3, the stand A⁷, on which a filling feeder or hopper is 25 mounted, the notched holding-plate N for the shipper N^X, Fig. 1, the automatically self-threading shuttle S to contain a supply of filling, such as a filling-carrier or bobbin b, and having a hole 4 in its front side wall, may 30 be and are all of usual or well-known construction—such, for instance, as in United States Patent No. 648,986, dated May 8, 1900. The filling-replenishing mechanism may be conveniently of the type shown in such patent, and a rock-shaft d' for controlling the 35 operation of the loom—as, for instance, to effect a change of filling—is shown mounted in suitable bearings below the breast-beam. Herein the rock-shaft d' has secured to it an 40 upturned arm d², projecting above the breast-beam and having pivoted to it at d³ the outer end of a latch d⁶, the latter extending across and beyond the breast-beam and having a reduced end d⁷ and a beveled or cam face 45 d¹⁸ on its under edge. (See Fig. 7.) The weft-hammer W has secured to its upper end an upturned head w, provided with a notched bunter w^X (see dotted lines, Figs. 2 and 7) to at times engage the end d⁷ of the 50 latch and move it outward to rock the arm d² and turn the rock-shaft d' in the direction of arrow 21. An upright projection w' on the head w travels beneath the end d⁷ of the latch, and at times it co-operates with the cam-face 55 d¹⁸, as will be referred to hereinafter. The latch is located at one side of the guide or stand m for the slide m' of the usual filling-fork m^X, and said latch has a lateral enlargement d⁸, on the under side of which is adjustably mounted a notched block d⁹, Figs. 2 and 60 7, substantially as provided for in United States Patent No. 677,607, dated July 2, 1901. A dog, to be described, when in engagement with the notched block d⁹ holds the latch 65 lifted, with its end d⁷ in the path of the bunter w^X, as the weft-hammer moves forward; but when the dog is withdrawn by or through

filling-induced movement of the feeler the latch drops, so that its end d⁷ is below the bunter, the latch then being inoperative, the 70 projection w' having passed from beneath the part d⁷ before the bunter has moved forward enough to engage it. When the weft-hammer swings back, the projection w' acts on the cam-face d¹⁸ and lifts the latch into the 75 position shown in Fig. 7, so that the dog can pass beneath the block d⁹, as before. In order to accelerate the movement of the latch to 80 inoperative position, a plunger d⁵, Fig. 2, is mounted in a socket in the top of the arm d² to bear on the cam-face d⁴ of the latch outside of its pivot d³, a spring s^X serving to 85 press the plunger upward, and thereby to assist gravity in depressing the rear end d⁷ of the latch. 85

We have shown a depending bracket or apron N² on the holding-plate N, Figs. 2, 3, and 4, to which is rigidly secured by bolts 5 a stand c^X, on which the feeler-support is 90 mounted to swing in a lateral path. This stand, as best shown in Figs. 3, 4, and 6, is of peculiar shape, its inner end being upturned, as at c, back of the breast-beam and then bent over at c', with an enlargement or boss c², having a socket c³ therein, the bottom of the boss 95 resting on the top of the breast-beam. The opposite end of the stand is extended upward in a diagonal direction, as at c⁴, and bent to clear the end of the holding-plate, as at c⁵, the extremity c⁶ of the extension being substantially parallel to the main part c^X and having a threaded hole c⁷ therein. On the rear 100 face of the part c⁴ are formed two parallel rearwardly-extended ears c⁸, which constitute a 105 guide and support for the outer free end of the swinging feeler-support and also serve to prevent it from lifting on its fulcrum. The feeler-support is best shown in Figs. 3 and 5, it being made as a casting having a body portion f', terminating at one end in an upturned 110 and then longitudinal flattened extension f², provided with a fulcrum-pin f³ to enter the socket c³ of the stand. At its other end the body has a dropped extension f⁴ of such thickness at f⁵ that it will freely enter between the 115 ears c⁸ of the stand, and there is an upright longitudinal web f⁶, extending to the outer end of the part f⁴, said web having a hole f⁷ therein which is opposite the hole c⁷ of the stand when the feeler-support is in position. An elongated recess f⁸ is made in the body 120 portion of the feeler-support, with a longitudinal slot f⁹, and the recess receives a lug g' on the bottom of a feeler-guide g, shown as an arm which projects toward the outer 125 end of the feeler-support and overhangs the ears c⁸, Fig. 3. A headed bolt g² passes up through the slot f⁹ and the guide g, extending above the top of the latter and through a sleeve or bushing 12, a washer 13, and nut 130 14 on the bolt, serving to clamp the feeler-guide in proper position on the feeler-support. The outer end of the guide has transverse parallel ribs g³ on its upper face, (shown

in Fig. 1 as connected at their outer ends,) and the feeler f is slidably mounted between them, the feeler being cut out or open at its rear end to lighten it and having an elongated feeling-face f^x . The guide g is longitudinally adjusted on the feeler-support until the feeler is directly opposite the opening 3 of the front box-wall b^x , when the lay beats up, the feeler at such time passing through the opening, and if the shuttle is boxed the feeler enters the shuttle through the hole 4. A threaded headed stud 25 is passed loosely through the hole f^7 in the outer end of the feeler-support, and then it is screwed into the hole c^1 in the stand, a check-nut 26 holding the stud fast, and a spring s^{10} is coiled around the stud between the end c^6 of the stand and the web f^6 , just behind it, to swing the feeler-support rearward against the head of the stud. The usual flat base or flange of the box-wall b^x is herein shown as enlarged or thickened at b^{2x} to engage the outer end of the feeler-guide below the feeler when the lay beats up, such part of the feeler-guide constituting a bunter, to thereby swing the feeler-support outward on its fulcrum f^8 against the spring s^{10} , as in Fig. 4. The stop-stud 25 is so adjusted that the front box-wall will always thus move the feeler-support on the forward beat of the lay, no matter whether the running speed of the loom may drop for a considerable number of picks per minute below the normal rate and irrespective of any adjustment of the box-wall. Consequently the feeler-guide will always maintain a certain fixed position relative to the longitudinal axis of the shuttle when the lay is on front center, and the feeler will be properly positioned for feeling action whenever the shuttle is in the box B^x — that is, on every other pick. The feeler is moved outward in its guide by engagement with the filling in the shuttle on alternate picks against the action of a spring, to be referred to, and such filling-induced movement of the feeler acts to move a dog-carrier and periodically withdraw the dog from the block d^9 , rendering the latch inoperative until substantial exhaustion of the filling. The dog is shown herein as a plate d^{10} , preferably of hardened steel, mounted on the end of a carrier, (shown as an arm d^{11}), having a downturned hub d^{12} to loosely embrace the sleeve or bushing 12 around the clamping-bolt g^2 , before described, the washer 13 projecting over the arm and holding it in place. The inner end of the dog-carrier overhangs the fulcrum f^8 of the feeler-support, and the dog slides on the upper face 30 of a part of the stand or guide for the filling-fork slide m' , while the outer end of the carrier is loosely and pivotally connected with the feeler by a pin d^{13} , secured to and upturned from the feeler. The inner lever-arm of the dog-carrier is the longer, so that the movement of the dog is greater than the stroke of the feeler. A spring s^{20} , surrounding the hub d^{12} of the carrier, is fixed at one end and at its other end

engages the carrier, the spring being so wound that it tends to project the feeler rearward and maintain the dog in engagement with the notched block d^9 . Filling-induced movement of the feeler is resisted by the spring, the latter effecting the return movement of the feeler and bringing the dog back to coöperate with the latch in well-known manner. Manifestly when the filling-induced movement of the feeler is too slight to withdraw the dog, as when the filling in the shuttle has been woven off to the desired extent, the latch will be engaged by its actuator (the weft-hammer) and moved to effect a change in the operation of the loom. If the front box-wall is changed after the feeler has been adjusted to effect the change in operation when the filling has been exhausted to a desired extent, the proper operation of the feeler will not be altered or interfered with by the construction hereinbefore described, and the same is true as concerns irregular movements of the lay. When the loom is running at high speed and the filling has been exhausted to the desired extent, the sudden swing of the feeler-support as the lay beats up tends to throw or jar the dog out of engagement with the latch, and to prevent this we have increased the weight of the dog-carrier by thickening it at d^{15} between its fulcrum and the dog. The swing of the feeler-support acts to cause this weighted part to hold the dog in engagement with the latch, though it does not interfere with proper filling-induced movement of the feeler before there is a substantial exhaustion of filling in the shuttle.

Our invention is not restricted to the precise construction and arrangement herein shown and described, for the same may be modified or changed in various particulars without departing from the spirit and scope of the invention.

Having fully described our invention, what we claim as new, and desire to secure by Letters Patent, is—

1. In a loom, a lay, a shuttle-box thereon, means, including a feeler, to control the operation of the loom, substantial exhaustion of the filling in the shuttle acting through the feeler to effect the actuation of said means, and a device moved by engagement with the wall of the shuttle-box on the beat of the lay, to properly position the feeler for its feeling action.

2. In a loom, a lay, a shuttle-box thereon, having an adjustable front wall, means, including a feeler, to control the operation of the loom, substantial exhaustion of the filling in the shuttle acting through the feeler to effect the actuation of said means, and a device moved by engagement with the front wall of the shuttle-box on the forward beat of the lay, to properly position the feeler for its feeling action.

3. In a loom, a lay, a shuttle-box thereon, means, including a feeler, to control the op-

- eration of the loom, substantial exhaustion of the filling in the shuttle acting through the feeler to effect the actuation of said means, and a movable support on which the feeler is mounted and relatively movable, the support being engaged and moved by the front wall of the shuttle-box on the forward beat of the lay to properly position the feeler for its feeling action upon the filling in the shuttle. 70
5. In a loom, a lay having a shuttle-box thereon, a shuttle to contain a supply of filling, means to control the operation of the loom, said means including a feeler to intermittently engage and be moved by the filling in the shuttle until substantial exhaustion of such filling, filling-induced movement of the feeler acting to maintain said means inoperative, and a movable feeler-support upon which the feeler is mounted and has its filling-induced movement, the front wall of the shuttle-box engaging and moving the feeler-support on the forward beat of the lay, to position the feeler with respect to the longitudinal axis of the filling in the shuttle when the latter is boxed. 75
10. 4. In a loom, a lay having a shuttle-box thereon, a shuttle to contain a supply of filling, means to control the operation of the loom, said means including a feeler to intermittently engage and be moved by the filling in the shuttle until substantial exhaustion of such filling, filling-induced movement of the feeler acting to maintain said means inoperative, and a movable feeler-support upon which the feeler is mounted and has its filling-induced movement, the front wall of the shuttle-box engaging and moving the feeler-support on the forward beat of the lay, to position the feeler with respect to the longitudinal axis of the filling in the shuttle when the latter is boxed. 80
15. 5. In a loom provided with filling-replenishing mechanism, a lay having a shuttle-box thereon, a shuttle to contain a supply of filling, means to control the operation of said mechanism, said means including a feeler, and a movable feeler-support upon which the feeler is yieldingly sustained, the front wall of the shuttle-box moving the feeler-support on the forward beat of the lay to present the feeler properly to intermittently engage and feel the filling in the shuttle. 85
20. 6. In a loom, a lay provided with a shuttle-box having an adjustable front wall, a shuttle to contain a supply of filling, means to control the operation of the loom, said means including a feeler intermittently moved by the filling in the shuttle upon alternate picks until substantial exhaustion of such filling, and a swinging feeler-support upon which the feeler is yieldingly mounted, the said support being engaged by the front wall of the shuttle-box on the forward beat of the lay to properly position the feeler relatively to the longitudinal axis of the filling in the shuttle, 90
25. in accordance with the adjustment of the front wall of the shuttle-box and irrespective of irregular movements of the lay. 95
30. 7. In a loom provided with filling-replenishing mechanism, a lay, having a shuttle-box thereon, a shuttle to contain a supply of filling, means, including a feeler, to control the time of operation of said mechanism, presence of a substantial amount of filling in the shuttle acting through the feeler to prevent the operation of said means, and means governed by engagement with the front wall of the shuttle-box on the forward beat of the lay to prevent accelerated or retarded action of the feeler due to variable movement of the lay. 100
35. 8. In a feeler-loom, a fixed stand, a feeler-support fulcrumed at one of its ends on the stand and having a sliding connection with the latter near its other end, a spring to move the support in one direction, an adjustable stop therefor, mounted on the stand, a spring-controlled feeler carried by the support and movable relatively thereto, and a guide on the support to govern the movement of the feeler thereupon. 105
9. In a feeler-loom, a fixed stand having an upturned end, and a horizontal guide projecting from the face of the stand near its other end, a feeler-support fulcrumed at one end on the upturned end of the stand and in sliding engagement at or near its free end with the guide, a substantially horizontal feeler-guide at the free end of and transverse to the support, a filling-feeler slidably mounted in the guide, and means to yieldingly control the movement of the feeler in its guide. 110
10. In a loom, the lay having a shuttle-box thereon provided with an apertured front wall, a shuttle to contain a supply of filling and having an opening in its side, a feeler-support fixedly fulcrumed at one end opposite the shuttle-box and provided with a bunter to engage the front wall of the shuttle-box on the forward beat of the lay, a spring and an adjustable stop, to govern the movement of the support toward the lay, a feeler-guide on the free end of the support, a feeler slidably mounted in the guide and adapted to pass through the shuttle-box wall and enter the shuttle on alternate beats of the lay, to feel the filling in the shuttle and be moved thereby until substantial exhaustion of such filling, a member to control the operation of the loom, an actuator for said member, and connections between the latter and the feeler to prevent co-operation of the actuator and said member until substantial exhaustion of the filling in the shuttle, movement of the feeler-support by the front wall of the shuttle-box positioning the feeler properly for its feeling action. 115
11. In a loom, means to control its operation, a lay having a shuttle-box thereon, a shuttle to contain a supply of filling, an actuator for said means, the latter including a feeler, a latch maintained inoperative by the presence and rendered operative by the substantial exhaustion of filling in the shuttle, acting by or through the feeler, the actuator then co-operating with the latch to effect a change in the operation of the loom, and a movable, 120
12. spring-controlled feeler-support on which the feeler is movably mounted, said support having a bunter to be engaged and moved by the front wall of the shuttle-box on the forward beat of the lay, to bring the feeler into position with relation to the longitudinal axis of the shuttle to co-operate properly with the filling therein on alternate beats of the lay. 125
13. 12. In a loom, a lay having a shuttle-box thereon, a shuttle to contain a supply of filling, means to control the operation of the loom, and an actuator for said means, the latter including a feeler to intermittently engage and be moved by the filling in the shut- 130

tle until substantial exhaustion of such filling, a latch, a dog to maintain it operative, a swinging, spring-controlled carrier for the dog, pivotally connected at one end with the 5 feeler, and a movable feeler-support on which the carrier is fulcrumed and having a guide for the feeler, the feeler-support being moved upon the forward beat of the lay by engagement with the front wall of the shuttle-box, 10 to properly position the feeler, filling-induced movement of the feeler swinging the carrier and through the dog rendering the latch inoperative, substantial exhaustion of the filling in the shuttle permitting the dog to retain 15 the latch in position to be engaged by the actuator, and thereby to effect the operation of the controlling means for the loom.

13. In a loom provided with filling-replenishing mechanism, a lay provided with a shuttle-box, a shuttle to contain a supply of filling, a swinging feeler-support moved by the front wall of the shuttle-box on the forward beat of the lay, a spring to move it oppositely, means to regulate such latter movement, a 20 feeler slidably mounted on the feeler-support, to intermittently engage and be moved by the filling in the shuttle as the lay beats up, a latch, a dog to maintain it operative, and a swinging, spring-controlled carrier for the 25 dog, fulcrumed on the feeler-support and operatively connected with the feeler, to be swung by filling-induced movement of the latter, thereby withdrawing the dog and rendering the latch inoperative intermittently 30 until substantial exhaustion of the filling in the shuttle, combined with an actuator to cooperate with and move the latch when operative, and controlling connections between the 35 latch and the replenishing mechanism, to effect the operation of the latter when the actuator moves the latch.

14. In a feeler-loom, a fixed stand, a feeler-support fulcrumed at one of its ends on the stand and having a sliding connection with 40 the latter near its other end, a spring to move the support in one direction, an adjustable 45

stop therefor, mounted on the stand, a longitudinally-adjustable feeler-guide on the support, a feeler slidably mounted in said guide, a dog-carrier fulcrumed on the guide and operatively connected at one end with the feeler, a dog on the opposite end of the carrier, and a spring to swing the carrier oppositely to movement thereof due to filling-induced action of the feeler. 50

55

15. In a feeler-loom, a fixed stand, a feeler-support fulcrumed at one of its ends on the stand and having a sliding connection with the latter near its other end, a spring to move the support in one direction, an adjustable 60 stop therefor, mounted on the stand, a feeler-guide on the outer end of the support, a feeler slidably mounted in said guide, a dog-carrier fulcrumed on the feeler-support and weighted adjacent its fulcrum, the outer end of the carrier being operatively connected with the feeler, a dog, on the inner end of the carrier, and a spring to control the swinging movement of the carrier and therethrough to move the feeler in opposition to filling-induced 65 movement of the feeler. 70

16. In a loom, a lay having a shuttle-box thereon, a shuttle to contain a supply of filling, means, including a feeler, to control the operation of the loom, substantial exhaustion 75 of the filling in the shuttle acting through the feeler to render said means operative, a spring-controlled feeler-support fixedly fulcrumed at its inner end and having the feeler mounted on its free, outer end, and a bunter on the 80 feeler-support, to be engaged and moved by the front wall of the shuttle-box to properly position the feeler for its feeling action on the forward beat of the lay.

In testimony whereof we have signed our 85 names to this specification in the presence of two subscribing witnesses.
